UNITED STATES PATENT OFFICE.

JOHN HUBLER, OF BRANDON, WISCONSIN.

SCUTCHING-MACHINE.

1,200,615.

Specification of Letters Patent. Patented Oct. 10, 1916.

Application filed April 11, 1916. Serial No. 90,328.

To all whom it may concern:

Be it known that I, JOHN HUBLER, a citizen of the United States, and resident of Brandon, in the county of Fond du Lac and 5 State of Wisconsin, have invented certain new and useful Improvements in Scutching-Machines; and I do hereby declare that the following is a full, clear, and exact description thereof.

10 My invention has for its object to provide a simple, effective and durable scutching machine for treating hemp or analogous fiber. The construction and arrangement of the machine is such that the hemp stalks are 15 taken from the breaking machine and fed between companion sets of traveling conveyers, constituting jaws, under compression. The jaws grip the stalks of the fiber at an intermediate point transversely of 20 their length and cause their free ends to travel over skeleton concave aprons. The said free ends are, during their travel, operated upon by oppositely rotative scutching elements having teeth and beaters there- 25 on, which travel in approximate alinement with the aprons and in a transverse direction with relation to the travel of the conveyer jaws, whereby the fibers are thoroughly beaten and combed as they travel 30 from end to end of the conveyer jaws, resulting in a separation of the "hurds", which will fall through the skeleton aprons and collection of the short fibers or "tow", which tow fibers are discharged by movement of 35 the scutching elements at the open sides of the aprons, while the long fibers, after being thoroughly combed, are delivered at the discharge end of the machine from between the jaws which together constitute a throat.

40 As one exemplification of my invention, I have shown a machine constructed to accomplish the functions just mentioned, but it is understood that I may, without departing from the spirit of my invention, vary the 45 details of the machine within the knowledge of the skilled mechanic.

With the above objects in view the invention consists in certain peculiarities of construction and combination of parts as hereinafter set forth with reference to the accompanying drawings and subsequently claimed.

In the drawings Figure 1 represents a cross-section of the machine, the section being indicated by line 1—1 of Fig. 2; Fig. 2, a longitudinal sectional elevation of the

same, the section being indicated by line 2—2 of Fig. 1; Fig. 3, a transverse sectional view through the feed end of the machine showing the various gear connections, the section being indicated by line 3—3 of Fig. 4, there being certain parts broken away to avoid confusion; Fig. 4, a longitudinal sectional elevation through one of the scutching elements or drums, the section being indicated by line 4—4 of Fig. 1; Fig. 5 is an enlarged detailed sectional elevation through a portion of the drum showing the structural features of one of the spring teeth, the series of which constitute the combing elements; 70 Fig. 6, a cross-section of the same, the section being indicated by line 6—6 of Fig. 5; Fig. 7 is a side elevation of a fragment of the chains showing the method of articulating the chain knuckles or couplings whereby 75 they are nested together closely; Fig. 8, a detailed cross-section of the conveyer chains which constitute the jaws, showing the method of gripping the fiber therebetween, and Fig. 9, an enlarged diagrammatic sec- 80 tional view through the conveyer jaws showing the hemp stalks fitted in the throat and gripped for operation, the free portions of the hemp being shown engaged by the beaters and combing elements of the scutch- 85 ing cylinders.

Referring by characters to the drawings, 1 represents a series of longitudinal and transverse ground sills of a frame, and 2 a series of uprights which serve as supports 90 for a longitudinally disposed track sill or table 3, the same being in practice approximately three-quarters of an inch or less in width, it being desirable to have the width at this point narrow due to the fact that it is 95 the point at which the stalks are gripped to be worked upon. Mounted to travel upon the upper surface of the track sill or table is the working stretch 4 of an endless conveyer chain, which chain at the feed end of 100 the machine is trained over a sprocket-wheel 5 and from thence over a drive sprocket-wheel 6 and back to the feed end of the machine over an idle sprocket-wheel 7, the sprocket-wheels 5 and 7 being mounted in 105 suitable bearings that are affixed to diagonally disposed brace struts of the frame, which struts are also secured to the ends of the track sill 3. The drive sprocket 6 is mounted upon a shaft 6' affixed to suitable 110 bearings upon the ground sills and the outer end of this shaft is in sprocket gear connec-

- tion with a stud shaft 8 that is journaled in bearings supported upon sill members that constitute part of a bridge frame having main cross-sills 10 and upright sills 11, the said bridge-frame is at the feed end of the machine and also serves to support all driving mechanism and the shafts of scutching elements or drums which will be hereinafter described in detail.
- 10 A longitudinally disposed presser foot frame 12 is positioned in alignment with the track sill 3 and over the same and it embodies a pair of cheek-bars 13 and a pair of spaced upper strut bars 14, which bars are connected by tie strips 15. The presser-foot frame is held in its suspended position at its rear end by upwardly inclined angle iron bars 12' which rise from the sill frame, and at its front end it is supported by the main cross-sill 10, as best shown in Figs. 2 and 3, the said cross-sill being fitted at the intersecting point of the strut bars 14 and the tie-strips 15.
- 25 The lower or working stretch 16 of an endless chain constitutes the companion member of the conveyer jaw 4 and the knuckles of the links of this chain stretch break joints with the knuckles of the lower chain stretch 4, as best shown in Figs. 2 and 30 7 of the drawings. The upper endless chain just described is trained at its feed end over a lower sprocket-wheel 17 and an upper sprocket-wheel 18 and the rear end of the chain is trained over a large sheave 18'.
- 35 The sheave 17 is mounted upon a block 17' which is carried by the presser-foot frame and is adapted to be adjusted slightly for belt tightening purposes. The sprocket-wheel 18 is journaled in boxes affixed to the strut bars 14, while the sheave 18' is journaled in bearings secured to the ends of the cheek-bars 13 of said presser-foot frame.
- 40 Mounted between the cheek-bars 13 are a series of vertically slideable shoes 19, which 45 shoes are guided by bolts 19' that extend through the cheek-bars and slots 20 with which the shoes are provided. The forward or toe ends of the sole of the shoes which engage the chain stretch 16 are curved upwardly, as shown, and the upper portion of the shoes have projecting therefrom pins 21 which are slideable in apertures of a tension bar 22, there being coiled springs surrounding each of the shoe pins 21, which coiled 50 springs are interposed between the lower face of the tension bar and the upper faces of the shoes, whereby the same are held in yieldable engagement with the chain stretch 16 previously mentioned. The tension of the series of shoes is simultaneously adjusted 55 by hanger bolts 23 which are secured to the tension bar and extend through cross-bars 14' that connect the strut bars 14. The hanger bolts are provided with upper and 60 lower nuts in threaded engagement there-

with, whereby the tension bar can be raised or lowered to regulate the tension of the shoes.

As best shown in Fig. 1 and the enlarged diagram view Fig. 9, the articulated chain stretches 4 and 16, which constitute traveling conveyer jaws, are guided transversely by metallic valance strips 24 that are secured to the track sill 3 and project above its upper surface and a corresponding pair 75 of valance strips 25 that are fastened to the lower shouldered portions of each shoe 19 and have projecting edges which form a biting contact with the upper edges of the lower valance strips when the machine is 80 not in operation. It is understood, however, that the chain stretches 4 and 16 together form a throat for the stalks of the hemp which are fed therebetween in a thin layer and when so fed the upper chain 85 stretch 16 will yield slightly to compensate for the thickness of the material, while the bite is insured by the spring-pressed shoes 19 which oppose expansion of the throat. In practice the sprocket 17 is adjusted upwardly so as to widen the throat at the point of feed slightly, whereby the material is readily grasped between the chains in their travel to the toe of the first shoe, which, due to its spring pressure, will then 95 tend to contract the throat in opposition to the thickness of the material passing therethrough.

Referring more particularly to Fig. 1 of the drawings the track sill 3, in effect, forms 100 the backbone of a pair of convex skeleton aprons A, which aprons comprise a series of longitudinal spaced slats 26 that are supported at intervals upon transversely disposed circular band sections 27, the inner 105 ends of which are secured to the sill 3 and the outer portions thereof are fitted to transversely disposed beams 1' that form part of the bed sill frame 1. The aprons are unobstructed at their lower sides, as shown, 110 whereby material may be discharged therefrom upon the ground, which material in hemp combing is commonly known as "tow".

The bridge-frame is provided with pairs of bearing sills 28, as best shown in Figs. 115 3 and 4 of the drawings, which sills are inclined outwardly and upwardly from the central portion of the machine preferably at an angle of 45° and are supported by suitable tie-bars. The bearing sills have 120 mounted thereon metallic ways 29 for companion pairs of boxes 30 each of which pairs are slideable upon the ways, being adjusted by threaded spindles 31 that are in link belt connection, as shown. Each pair 125 of aligned boxes serve as supports for drum shafts 32, which overhang the concavo-convex aprons and are unsupported at their opposite ends. Motion in opposite directions is imparted to the pair of drum shafts from 130

a main drive shaft 33. This shaft carries a sprocket-wheel 34 that is in chain belt connection with a corresponding sprocket-wheel 34' that is mounted upon one of the drum shafts and the opposite drum shaft has a sprocket-wheel 35', as indicated in dotted lines Fig. 3, which sprocket-wheel is in link belt connection with a corresponding sprocket-wheel 35' that is fixed on a countershaft 36. The said counter-shaft 36 is in beveled gear connection with a transverse shaft 37, which shaft is also in beveled gear connection with the main drive shaft 33 and said main drive shaft is likewise in beveled gear connection with the shaft 8 and a stud-shaft 18', upon which is mounted the sprocket-pinion 18, the same being the driving pinion of the upper endless chain that has its working stretch 16 arranged to 20 form one of the traveling conveyer jaws.

For the purpose of regulating the tension of the chain belts which impart motion to the drum shafts 32, each of the same is provided with a belt tightener 38 of ordinary construction, one of the same being shown in full in Fig. 3 of the drawings. Each drum shaft has mounted thereon spider arms 39 that support a shell-like metallic drum 40, each of the same being nested within a concavo-convexed apron A, as shown in Fig. 1. These drums constitute scutching elements of the machine and are provided with a series of beater blades 41 having flexible wiper strips 41' that project from their ends, which wiper strips are preferably composed of rubber or other yieldable substance and are adapted to engage the free ends of the fiber, whereby a proper beating action is imparted thereto 40 coincident to rotation of the drums. In this exemplification of my invention I have shown the beater blades as being rigidly attached to the surface of the drum, but, in some instances, I may employ beater blades 45 that are arranged in spring hinge connection with the drum surfaces whereby they will yield backwardly coincident to engagement with the product worked upon.

Alternating the series of beater blades 50 the surface of the drum has projecting therefrom a series of teeth 42 which are preferably of the spring tang variety with their outer ends bent backwardly with relation to the direction of travel of the 55 drums, their travel being indicated by the arrows in Fig. 1.

As best shown in Figs. 5 and 6 of the drawings, the series of spring teeth 42 at their inner ends are coiled about pipe sections 43 with their short ends secured by bolts 44, the same being fitted in either pair of a set of openings in the pipes to individually regulate the tension upon the working ends of the teeth. In order to 65 provide a universal adjustment as to ten-

sion of the teeth of each series and to support the pipe sections 43, the drum has secured thereto reinforcing rings 45 and also companion sets of bearing blocks 46 for the pipe sections and the said pipe sections are held against rotation in their bearing blocks by plug pins 46' which pass through apertures in the pipe sections and bearing blocks, whereby the said pipe sections are locked. By twisting the pipe sections a quarter turn in the proper direction the tension on the teeth will be increased and after this winding operation the plugs 14 are reinserted in position to prevent twisting of the pipe. As shown in Fig. 6, 80 the tension upon the teeth is maintained by said teeth engaging the ends of slots 47 with which the shell of the drum is provided and back movement of the teeth is permitted due to the length of the slot. 85 Thus the teeth are permitted a certain yield backward coincident to a combing operation. It is manifest, however, that the specific arrangement of the teeth and the means of tensioning the same is immaterial 90 so far as the functioning of the machine is concerned.

As indicated by the dotted line α in Fig. 2 of the drawings, the position of the axis of each drum is shown relative to the upward inclination of the conveyer jaws of chain stretches 4 and 16, the said axis being upon a horizontal plane and at the feed end of the machine the axis of each drum is upon a higher plane than the feed throat, 100 while at the discharge end it is upon a lower plane. Thus the teeth of the drum at the feed end are consequently farther away from the concaved apron surface than at the discharge end so that a coarser scutching or combing operation is effected initially at said feed end and a correspondingly finer combing operation is produced at the discharge end due to the fact that the beating blades and ends of the teeth at said feed 110 end are close to the concave apron surface. It will also be observed that the scutching elements or drums can be adjusted toward or away from the aprons to accommodate varying conditions and quantity of the material to be operated upon. 115

Referring especially to the diagram view, Fig. 8, in the operation of the machine, the hemp stalks from the break are inserted at the feed end between the chain stretches 4 and 16 approximately at a central point of the length of the material and as the chain stretches revolve at the same speed they bite the thin layer of fiber tightly due to the spring tension of the shoes which rise 120 slightly to accommodate or expand the throat between said chain stretches, whereby the material is fed from the feed end slowly toward the discharge end of the machine. The free end, draping upon the concavo- 130

convexed surface of the skeleton aprons, in its travel is subjected to a beating and combing operation in a direction transverse to the travel of the material or in alinement 5 with the strands thereof. Thus the material is combed and beaten continuously throughout its travel, whereby all "hurds" are extracted. The hurds fall through the slats of the aprons and the "tow," which is separated 10 from the long fiber, is discharged to the sides of the aprons, while the long fiber is straightened out and combed in a thorough manner before it reaches the point of final discharge at the rear end of the machine. It will also be noticed that, owing 15 to the constant pull in opposite directions upon the fiber strands, the strain is approximately divided from the central point at which they are held, but this pull upon the 20 strands in opposite directions will permit of slight back and forth movement of the hemp through the throat, whereby the point of gripping is also worked upon and combed and relieved of both hurds and short 25 strands. Thus it will be seen that, in the operation of the machine, the hurds are first separated and discharged at one point, the tow at another, and the finished "line fiber" finally discharged at the rear end of the 30 machine, making a complete separation of the by-products.

I claim:

1. A machine of the character described comprising a pair of longitudinally traveling endless conveyer jaws forming a throat therebetween for fiber stalks and adapted to feed the same therethrough, the bite of the jaws being transverse of the stalks, companion skeleton concavo-convexed aprons 35 extending from the conveyer jaws in opposite directions over which the free ends of the stalks travel, and revoluble toothed scutching drums nested within the aprons adapted to comb both ends of the fiber as 40 it travels to the discharge end thereof and means for adjusting the drums relative to the conveyer throat and aprons.

2. A machine of the character described comprising a pair of endless conveyers having opposed working stretches forming a throat therebetween for fiber stalks adapted to be fed therethrough, the bite of the conveyers being transverse of the stalks, means for tensioning the bite of said conveyers, 50 companion sets of skeleton concavo-convexed aprons extending from the working stretches of the conveyers in opposite directions over which the free ends of the fiber stalks travel, oppositely disposed revoluble 55 drums nested within the aprons, a series of beaters and teeth extending from the surface of the drums in juxtaposition to the aprons 60

adapted to operate upon the material as it is caused to travel with the conveyers, and means for adjusting the drums relative to the conveyer throat and aprons.

3. A machine of the character described comprising a pair of endless chains having articulated stretches to constitute gripping jaws forming a throat therebetween for fiber stalks, spring-pressed shoes opposing one of the chain stretches, a rail opposing the opposite chain stretch, concavo-convexed skeleton conveyers extending from the companion chain stretches in opposite 75 directions, oppositely rotative drums nested within the aprons, and yieldable teeth extending from the surfaces of said drums for engagement with the free ends of the fibrous material coincident to its travel with 80 the conveyer from end to end of the machine.

4. A machine of the character described comprising a pair of endless chains having articulated stretches to constitute gripping jaws forming a throat therebetween for fiber 85 stalks, spring-pressed shoes opposing one of the chain stretches, a rail opposing the opposite chain stretch, concavo-convexed skeleton conveyers extending from the companion chain stretches in opposite directions, oppositely rotative drums nested within the aprons, spring teeth extending from the surfaces of said drums for engagement 90 with the free ends of the fibrous material coincident to its travel with the conveyer 95 from end to end of the machine, and means for adjusting the drums with relation to the juxtaposed surfaces of the aforesaid concavo-convexed aprons.

5. A machine of the character described 100 comprising a pair of longitudinally traveling endless conveyer chains the working stretches of which are superimposed, a fixed support for one of the stretches, a yieldable pressure means engageable with the other 105 working stretch, concavo-convexed skeleton aprons extending from the working stretches of said conveyers, toothed oppositely revoluble drums nested within the aprons, series of teeth and beater blades carried by the drums and associated with the juxtaposed surfaces 110 of the aprons, means for adjusting the drums relative to the aprons, and means for imparting synchronous drive to the conveyer chains.

In testimony that I claim the foregoing I have hereunto set my hand at Ripon, in the county of Fond du Lac and State of Wisconsin, in the presence of two witnesses.

JOHN HUBLER.

Witnesses:

R. C. STUART,
